CLAIM

I claim the ornamental design for a canine communication device, as shown and described.

DESCRIPTION

FIG. 1 is a top perspective view of a canine communication device according to the present invention;

FIG. 2 is a top view of the invention.

FIG. 3 is a right side view of the invention; and

FIG. 4 is a right side view of the invention; and,

FIG. 5 is a left side view of the invention.

1 Claim, 5 Drawing Sheets

FIG 1

FIG 2

FIG 3

FIG 4

FIG 5
